TUNING CONDENSER MOUNTING

Gerald J. Barry, Philadelphia, Pa., assignor to
Philco Radio and Television Corporation, Phil-
adelphie, Pa., a corporation of Delaware

Application April 16, 1937, Serial No. 137,373

6 Claims. (Cl. 248—358)

This invention relates to an improved mounting for the tuning element or unit of a radio receiver or the like, and has for its principal object the provision of a simple mounting which may be easily and economically manufactured and assembled, and which is adapted to mount the tuning unit floatingly and adjustably for the purposes hereinafter set forth.

Another object of the invention is to provide a novel mounting of this character which comprises interlocking parts for mounting the tuning unit on a support or base free of mechanical attachment to the support, and which embodies a single mechanical attachment between the tuning unit and a mounting element serving additionally to permit adjustment of the mounting of the tuning unit to bring the control shaft thereof into alignment with the opening in the radio cabinet.

A further object of the invention is to provide a novel mounting employing specially formed mounting elements which are adapted for the purpose in view.

Other objects and features of the invention will appear more clearly hereinafter.

25 In the accompanying drawing:

Fig. 1 is a front elevational view of the condenser unit mounting;

Fig. 2 is a side elevational view of the mounting;

30 Fig. 3 is a fragmentary perspective view illustrating one of the front mounting feet of the device;

Fig. 4 is a perspective view of one of the resilient members employed;

35 Fig. 5 is a sectional view of a resilient member;

Fig. 6 is a detail sectional view taken through the rear mounting of the device; and

Fig. 7 is a perspective view of the rear mounting member.

40 Referring to Figs. 1 and 2, there is shown a support or base 1 upon which the tuning condenser unit 2 is floatingly and adjustably mounted in accordance with the present invention. The support 1 and the tuning condenser unit 2 may 45 take any suitable forms, those illustrated being chosen merely for the purpose of disclosure. It will be understood, that the tuning condenser unit may include other elements beside the tuning condenser itself. As conventionally formed, the 50 tuning condenser unit comprises a frame 3 carrying a plurality of aligned condensers 4, in the present instance, two condensers being shown. It will be understood, of course, that the condenser unit may comprise any desired number 55 of tuning condensers. The condenser unit is

provided with the usual control shaft 5 which is adapted to adjust the several condensers of the unit, as well understood, and there is also provided the usual shaft 6 which is adapted to carry the tuning indicator or dial. When the radio receiver embodying the tuning condenser unit is assembled within the usual radio cabinet, the control shaft 5 is adapted to extend through an opening in the front wall of the cabinet in order that it may be accessible outside the cabinet.

The support or base 1 is preferably formed of sheet metal in the form of an inverted box, thus providing an elevated horizontal supporting panel.

15 It is desirable to floatingly mount the tuning unit of a radio receiver so as to isolate the said unit from vibration and thus avoid microphonics and undesirable vibration of the parts of the tuning unit which are sensitive to mechanical disturbances. The commercial manufacture of such a floating mounting, however, requires broad tolerances in the mounting and makes it impossible to align the tuning control shaft exactly with the hole in the cabinet through which the shaft extends. By the present invention, there 20 is provided a novel floating or resilient mounting for the tuning condenser unit and there is also provided means for adjusting the mounting of the unit to vary the position of the tuning control shaft and thus overcome the inaccuracies 25 incurred by the required tolerances of manufacture above mentioned. Moreover, the mounting provided by the invention is extremely simple and easy to assemble and it reduces the cost of manufacture and assembly to a minimum.

30 In accordance with the invention, at the front end of the condenser unit, there is provided a transverse member 7 which is secured rigidly to the frame 3 in any suitable manner, for example by means of rivets 8. The end portions of 40 member 7 are formed so as to provide mounting feet 9, one of which is clearly shown in Fig. 3. These mounting feet are of bifurcated or claw-like structure, as clearly illustrated, for a purpose which will appear presently.

45 A resilient member 10, as shown clearly in Figs. 4 and 5, is adapted to fit over each of the front mounting feet 9. To this end, the resilient member 10 is recessed as clearly shown in Fig. 5 in order that it may fit over a mounting foot 9 50 and may receive the extending upper and lower arms of the mounting foot. Further, as shown in Fig. 5, the resilient member 10 is formed so that there is a substantial thickness of resilient material below the upper recess of the member. 55

- The resilient member 10 is also provided with a slot 11 disposed as clearly illustrated. Each of the resilient members, which are shaped as illustrated and described, may be formed of any suitable material such as live rubber. These members may be manufactured in any suitable manner, for example by molding the material to the desired form following molding practices which are commonly employed.
- 10 The support or base 1 is provided with spaced openings which are adapted to receive the front mounting feet 9 with the resilient members 10 thereon, as shown in Figs. 1 and 2. These openings are of such size that the lower portions of 15 the mounting feet 9 and the resilient members 10 fitted thereon may be inserted through the openings and the mounting feet then moved so as to cause the slots 11 to receive and engage the edge portions of the base at the said openings.
- 20 In this manner, the resilient mounting members are interlocked with the base free of mechanical attachment thereto. The substantial thickness of resilient material above the slot 11 of each resilient mounting member serves to amply cushion 25 the front end of the tuning condenser unit with respect to the support or base. The cushioned front mounting feet also serve cooperatively with a rear mounting foot to prevent displacement of the supported unit as described below.
- 30 In further accordance with the invention, at the rear of the tuning condenser unit, there is provided a mounting member 12 formed as clearly shown in Fig. 7. This mounting member is provided with a lug 13 which is adapted to seat 35 in an elongated opening 14 provided in the rear wall of frame 3 as clearly shown in Fig. 6. The member 12 is also provided with an elongated opening 15 adapted to receive a screw 16 carried by the rear wall of frame 3 as shown clearly in 40 Fig. 6. It will be seen that by virtue of lug 13 and the screw 16, the mounting member 12 is held against lateral movement and, at the same time, the rear of the frame 3 may be adjusted vertically and held in adjusted position by means 45 of the screw 16. A shake-proof washer 16a is preferably employed to prevent loosening of the screw after adjustment.
- The mounting member 12 is also provided with a bifurcated foot portion 17 similar to the front mounting feet 9 above described. Mounting foot 17 is likewise adapted to receive a resilient member 18 similar to the resilient members 10. The support or base 1 is provided with an opening 19 which is adapted to receive the rear mounting 50 foot 17 and the resilient member 18 carried thereby, as illustrated in Fig. 6, the slotted resilient member 18 being interlockable with the edge of the support or base at the opening 19.
- The several openings in the support 1 for the 55 mounting feet 9 and 17 are of sufficient width to fit snugly against the sides of the resilient members 10 and 18. In this way, the tuning unit is prevented from moving sideways when viewed from the front. The length of the several openings is sufficient to permit the mounting feet to be inverted in them when the resilient members are in place. To prevent forward or backward movement of the tuning unit, the front mounting feet 9 extend forward while the rear mounting 60 foot 17 extends backward. As may be seen in Fig. 6, there is a cushion of rubber between the support 1 and foot 17 which prevents the foot from moving to the left in the drawing. In the complete assembly the feet 9 prevent forward 65 movement and the foot 17 prevents rearward

movement, the front and back edges of the front and rear openings respectively being spaced to provide a snug fit. It will be noted that possible movement in any direction will be eventually limited by a metal-to-metal contact after all the rubber has been displaced.

The complete mounting may be easily and rapidly assembled as follows: Assume that the parts are completely disassembled, the resilient members 10 are placed on the front mounting 10 feet 9 and the resilient member 18 is placed on the rear mounting foot 17. The mounting member 11 carrying the resilient member 18 is then inserted in the rear opening 18 and interlocked therewith, as illustrated in Fig. 6. To do this, 15 the operator places the members 12 and 18 in the opening in a tilted position so that the left lower corner of the resilient member 18, as viewed in Fig. 6, is in the opening 19 and the front of the slot 11 is engaged with the left edge of the opening. In this position the member 12 is inclined toward the right and the bottom of the curved edge 20 rests against the right edge of the opening. By rotating the top of 12 clockwise about the left edge of the opening as an axis, the member will be forced to its proper position, the curved surface 20 sliding on the right edge of the opening and acting as a cam surface to urge the member to position. However, before this last step, the unit 2 is placed on the base of an 30 angle (downward to the left in Fig. 2) and the front members 7 carrying resilient members 10 are inserted and interlocked with the front openings following the same procedure; i. e., inserting at an angle and rotating to the proper 35 position. In this operation, the curved edge 21 (Fig. 3) rides on the rear edge of the front opening and acts as a cam surface to urge members 7 to position. The member 12 is then rotated to its proper position as described above. (In Fig. 2 40 the top of member 12 is moved to the left.) This brings the rear wall of the frame 3 and the mounting member 12 into cooperative relation with the lug 13 extending into the opening 14. The screw 16 is then inserted through the opening 15 and is 45 threadedly engaged with the rear wall of the condenser frame. The mounting is then completely assembled and, in order to align the tuning control shaft 5 with the opening therefor in the front wall of the radio cabinet, it is merely necessary 50 to slightly loosen screw 16 and raise or lower the rear of the tuning condenser unit. When the proper position of the unit is obtained, the screw 16 is tightened to maintain the adjustment. When completely assembled, the edges 20 and 55 21 are free of contact with base 1.

It will be noted that the front and rear resilient mounting elements are interlocked with the support or base free of mechanical attachment thereto, the only attachment element employed in the 60 device being the screw 16 which serves to adjustably secure the rear of the tuning condenser unit to the rear mounting member 12. By virtue of this construction, the device is adapted for rapid assembly at low cost. Thus, the device 65 lends itself particularly to modern mass production methods and it effects a substantial saving in the cost of manufacture of a radio receiver. In fact, it has been found that this mounting reduces, by five or six, the number of manual operations heretofore required in the assembly of the tuning condenser mountings which have been employed. Moreover, by reducing the number of attachment elements to one, as compared to several employed in prior devices, the present in- 70 75

vention greatly facilitates the assembly process and effects a further economy in production.

It will be noted also that the invention provides a three-point resilient mounting for the condenser unit which isolates the unit mechanically from the support or base and thus eliminates any possibility of microphonics, particularly since the resilient members 16 and 18 provide the desired resilient yet rugged supporting cushion at each of the three mounting points. Furthermore, the invention provides a very simple means for adjusting the position of the tuning condenser unit to obtain the required alignment of the tuning control shaft with the hole therefor in the front wall of the cabinet.

It will be understood, of course, that the invention has been illustrated and described with reference to a specific preferred form for the purpose of disclosure only, and that the invention is not limited to this specific form but is capable of various modifications as will be apparent to persons skilled in the art.

I claim:

1. Apparatus for mounting a tuning element of a radio receiver or the like, comprising a supporting base having openings therein, a tuning element unit, a mounting member having bifurcated feet carried by said unit at one end thereof, resilient members shaped to fit over said feet and adapted to interlock with said base at said openings to resiliently support said end, and means for resiliently mounting the opposite end of said unit on said base.

2. Apparatus for mounting a tuning element of a radio receiver or the like, comprising a supporting base having openings therein, a tuning element unit, a mounting member having bifurcated feet carried by said unit at one end thereof, resilient members shaped to fit over said feet and having slotted portions adapted to interlock with the edge of said base at some of said openings to resiliently support said end, a mounting member having a bifurcated portion, a resilient member shaped to fit over said portion and having a slotted portion adapted to interlock with the edge of said base at another of said openings to resiliently support said last-mentioned mounting member, and means for mechanically attaching said last-mentioned mounting member to the opposite end of said unit.

3. A mounting for a unit of a radio receiver or the like, comprising a supporting base having openings therein, a mounting member having an extending bifurcated foot and a recessed resilient element thereon adapted to interlock with said base at one of said openings, a mounting member on said unit having an extending bifurcated foot and a recessed resilient element thereon adapted

to interlock with said base at another of said openings, and mechanical attachment means for attaching said first-mentioned mounting member to said unit.

4. A mounting for a unit of a radio receiver or the like, comprising a supporting base having openings therein, a mounting member having an extending claw-like foot and a resilient element thereon insertable in one of said openings in interlocking relation with said base, said member having a cam surface adapted to engage an edge of said opening to urge said member into position, a mounting member on said unit having an extending claw-like foot and a resilient element thereon insertable in another of said openings in interlocking relation with said base, said last-mentioned member having a cam surface adapted to engage an edge of said other opening to urge said member into position, and mechanical attachment means for attaching said first-mentioned mounting member to said unit.

5. Apparatus for mounting a tuning unit of a radio receiver or the like, comprising a supporting base, a tuning unit including a tuning condenser having at least one extending shaft adapted to be inserted in a wall opening of a receiver cabinet, resilient means at the end of said unit from which said shaft extends having bifurcated feet interlockable with said support to resiliently support said end, a mounting member carrying resilient means having bifurcated feet interlockable with said support at the opposite end of said unit to resiliently support said mounting member, and means for adjustably attaching said mounting member to the said opposite end of said unit to permit variation of the position of said shaft so as to align the shaft with said wall opening.

6. Apparatus for mounting a tuning shaft of a radio receiver or the like, comprising a supporting base having openings therein, a tuning unit including a tuning condenser having at least one extending shaft adapted to be inserted in a wall opening of a receiver cabinet, bifurcated feet carried by said unit at the end thereof from which said shaft extends, resilient members shaped to fit over said feet and having slotted portions adapted to interlock with the edge of said base at some of said openings to resiliently support said end, a mounting member having a bifurcated portion, a resilient member shaped to fit over said portion and having a slotted portion adapted to interlock with the edge of said base at another of said openings to resiliently support said mounting member, and means for adjustably attaching said mounting member to the opposite end of said unit to permit variation of the position of said shaft so as to align the shaft with said wall opening.

GERALD J. BARRY.
